(57) **CLAIM**

The ornamental design for a protective case for watch, as shown and described.

DESCRIPTION

FIG. 1 is a front perspective view of a protective case for watch design showing my new design.

FIG. 2 is a rear perspective view of a protective case for watch.

FIG. 3 is a front view of a protective case for watch.

FIG. 4 is a rear view of a protective case for watch.

FIG. 5 is a left side view of a protective case for watch.

FIG. 6 is a right side view of a protective case for watch.

FIG. 7 is a top view of a protective case for watch; and,

FIG. 8 is a bottom view of a protective case for watch.

The shading shown in the drawings is utilized to illustrate surface contours of the protective case for watch and forms no part of the claimed design.

The broken lines in the figures illustrate portions of the protective case for watch that form no part of the claimed design.
